Specification of Letters Patent.

Patented Dec. 8, 1914.

Application filed January 23, 1895. Serial No. 535,986.

To all whom it may concern:

Be it known that I, FRANCIS C. OSBORN, a citizen of the United States, residing at Detroit, county of Wayne, State of Michigan, have invented a certain new and useful Improvement in Cash-Registers, and declare the following to be a full, clear, and exact description of the same, such as will enable others skilled in the art to which it pertains to make and use the same, reference being had to the accompanying drawings, which form a part of this specification.

My invention relates to cash registers of that class in which there is employed mechanism adapted to produce the exposure of an indicating tablet and at the same time operate a registering mechanism adapted to produce a register of the total amount of the sums indicated by all the tablets that are brought to indicating position.

In carrying my invention into effect, I employ means for giving to the tablet a primary movement, which movement sets it in position to be operated upon by a secondary actuator. I also employ means by which each key, after having been once depressed to bring about the primary actuating movement, is locked against a second depression before the indicating tablet has completed its movement to its indicating position and dropped therefrom. I also employ means for ringing the alarm bell with the depression of the key at the time it brings about the primary actuating movement or setting movement of the tablet.

I further employ, in connection with the indicating devices, a registering mechanism in which separate counters are so arranged that the amounts in units, tens, hundreds or in any higher denominations, may be separately and independently registered, but wherein the amounts registered on the separate registers may be transferred in part to the registers for the next higher denominations. In other words, in the instance of my invention which I propose to describe, I show three separate and distinct counters or registers, one intended for the registration of units, another for tens and the third for hundreds. Sales in units, tens or hundreds will be directly registered on the respective registers. The units register will be capable of registering amounts in tens and hundreds if desired. The tens

register will be capable of registering amounts in hundreds and thousands if desired. The hundreds register will be capable of registering amounts in thousands and ten thousands or any higher denominations. Thus a separate and distinct register is effected of all the sales in the several denominations. When desired, the register will be capable of effecting a transfer to the registers for the next higher denomination, whereby the tens and hundreds which may be registered upon the units register will be transferred first to the tens register, while the hundreds and thousands either registered directly upon the tens register or transferred thereto from the units register may, if desired, be transferred to the hundreds register. By thus transferring from the units register only the tens and hundreds and from the tens register only the hundreds and thousands, a total of the entire amounts will be effected on all of the registers taken together, and may be read from the register wheels of all of the registers.

In order that confusion may not result in effecting the transfers from the registers to the registers of the next higher order, it is necessary that the amounts so transferred should be deducted from the register from which the transfer is made. By transferring the units and tens to the total adder in this way, the employment of complicated transferring mechanism is avoided, which permits the employment of fewer and lighter parts, both in the counting mechanism and the devices which actuate the same, contributing not only to a reduction in the cost of the apparatus, but the ease of operation.

I make use of other novel devices and combinations of devices which will be hereinafter more fully referred to and claimed.

In the accompanying drawings which illustrate my invention, Figure 1 is a perspective view of the apparatus with a portion of the casing and the counters removed; Fig. 2 is a vertical cross-section, the counters being omitted; Fig. 3, a detail view of one end of the till-cover showing the bell-operating devices; Fig. 4 an enlarged perspective view of the bell-hammer and its operating lever; Fig. 5 is a perspective view of the counters, the mechanism at the right-hand end of the figure being the unit counter, the

central portion the tens counter, and the mechanism at the left-hand the hundreds counter; Fig. 6 is a cross-section on the line 6^a of Fig. 5, looking to the right; Fig. 7, a cross-section on the line 7^a of Fig. 5, looking to the right; Fig. 8, a cross-section on the line 8^a of Fig. 5, looking to the right. Fig. 9 is a cross-section on the line 9^a of Fig. 5, looking to the left and Fig. 10 a vertical cross sectional view through the machine, and Fig. 11 represents a detail perspective view showing the wrench end of the units wheel screw shaft.

The primary actuators for the tablet rods are the keys 1 pivoted on a cross-bar 1^a, and these keys are arranged in three sets, *i. e.*, the unit keys at the right, the tens keys in the middle, and the dollar keys at the left. There are nine unit keys, nine tens keys, and ten dollar keys, and each set is separated by a wide space, as seen in Fig. 1.

The secondary actuator consists of levers 8 (Figs. 1 and 3), which constitute the end-plates of the till-cover 2, to which is secured the operating handle 2^a. The indicating tablets are indicated at 3^a and are mounted upon vertically moving tablet rods 3. These rods move vertically in a frame 30 extending across the machine and secured to the end-plates. This frame has an upper horizontal flange 3^b and a lower horizontal flange 3^c, and upon which lower flange the tablet rods are supported in their unexposed positions by means of studs 3^d projecting from the front sides of the tablet rods. The lower end of each tablet rod is slotted, as shown at 3^e (Fig. 1), and into the slot of each rod projects the toe 4 of a key lever 1. The depression of a key lever elevates its tablet rod a short distance, and places a stud 5 at the lower rear end of the tablet rod in position to be engaged by the mechanism of the secondary actuator.

The secondary actuator operates a pair of levers 6, which are pivoted on the bar 9 at the front of the machine. The levers 6 are connected with the secondary actuator 8 by means of curved arms 7 (Fig. 1), whose points of connection with the levers are directly underneath the pivot or fulcrum 8^a of the actuator 8 which is the pivot of the till cover. The rear ends of levers 6 engage with the cross-bar 10^a, which is part of a vertically sliding frame composed of two vertical end-plates 10, the cross-bar 10^a and a cross-bar 10^b. This frame carries a lifting bar 11, which is carried by two arms 12 pivoted at 12^a to the plates 10. The vertically moving frame moves in guides 10^c and 10^d, and on these guides, or on any other stationary part of the frame, are secured two guides 13 and 14, which guide the lifting bar 11 into and out of the path of the studs 5 on the rear of the tablet rods. Thus

when the frame 10 is elevated through the opening of the tilt-cover, the shoulder 12^b (Fig. 2) on the arm 12 strikes the stationary guide pin 13 and causes the lifting bar 11 to move forward into engagement with the stud 5 of any one or more of the tablet-rods which may have been partially elevated by the key movement. The upward movement of the lifting bar before the shoulder 12^b strikes the pin 13, is sufficient to allow the upper surface of the lifting bar to clear the studs 5 of the tablet-rods remaining in their normal positions. When the lifting bar descends, it strikes the stationary guide 75 14 and is thrown out of engagement with the tablet-rods.

The upward movements of the tablet rods actuate segments which engage with the primary wheels of the counters. Since there are three sets of counters, three such segments are provided, *viz.*, segment 17 for the hundreds counter, segment 17^a for the tens, and segment 17^b for the units counter. These segments are carried by three shafts, one of which, 17^a, which is the shaft carrying the segment 17, is shown in Fig. 2. These shafts are carried by suitable bearings or brackets projecting from the frame through which the tablet rods pass, one of such brackets, 17^c, being shown at the left-hand end of Fig. 1. The segments referred to are provided with operating bars 16, 16^a and 16^b respectively, the segments being secured at one end of the bars, and the other ends of the bars are secured to arms 17^c, 17^d and 17^e respectively, which arms are secured to the shafts 17^a. The operating bars 16, 16^a and 16^b are actuated by the tablet rods through studs 15 projecting from the front faces of the tablet rods. These studs, as shown in Fig. 1, are so located on the tablet rods as to move the segments 17, 17^a and 17^b through a certain angle according to the numerical value of the respective tablet rods; that is to say, the tablet rod 10^c having the lowest numerical value, *i. e.*, the tablet bearing the numeral 1 of either the units, tens or hundreds tablets, has its stud 15 farthest down the rod, so that before the stud strikes the operating bar, the tablet rod will almost have reached the end of its upward stroke, and the angle through which the segment is moved by the tablet rod in completing the upward stroke will be equal to 1, or in other words, this movement of the segment will rotate the primary wheel of the counter a distance which will result in its respective registering wheel being moved one space. The studs on the other tablet rods are each successively and equal distances higher than the preceding one, so that the relative angular movements imparted thereby to the segments will be correspondingly greater; that is to say, if, for instance, the tablet bearing the numeral 5 120 125 129

- of either set is elevated, the segment actuated thereby will be moved through an angle equal to 5, and the primary wheel of the counter actuated thereby will move 5 through a corresponding angular distance, the effect of which will be to move its respective registering wheel a distance of five spaces, as will be hereinafter more fully described.
- 10 The tablet rods when raised to their indicating positions by the secondary actuator, are held in the exposed position by a locking bar 18 which extends across the entire series of tablet rods and is carried by the 15 arms 18^a of a pair of double bell-crank levers which are pivoted on the rod 18^b. The arms 18^c of these levers are connected by a rod 18^d which extends under the entire series of key levers, as most clearly seen in 20 Fig. 2. The downward projecting arms 18^c of these levers are connected to spiral springs 18^e whose other ends are secured to studs on the end-plates of the casing and act to throw the locking bar 18 against the 25 tablet rods, and the lifting bar 18^d upward to return the key levers to their normal positions.
- The operation of the parts just described is as follows: Upon depressing a key lever, 30 the two bell-crank levers are tilted on their pivots through the engagement of the key lever with the cross-bar 18^d, and this movement throws the locking bar 18 forward away from the tablet rods. The depression 35 of the key lever, as before explained, partly elevates a tablet rod, and upon opening the till cover, this tablet rod is raised to its indicating position by the action of the secondary actuator. The key lever after being depressed is held in that position by the locking device 19, which is carried by a rod 19^a and engages with the shoulders 19^b of the key levers; the normal position being that of Fig. 2. The rod 19^a is provided 40 with a downwardly extending lever 19^c (Fig. 1), whose lower end is connected with one end of a spring 19^d, the other end of which is connected with a stud on the casing. At the lower end of the lever on the 45 inner side is a lug 19^e which projects into the path of a pin 18^x (Figs. 1 and 3) on actuator 8. When a key lever is depressed, the locking device is rocked forward through its engagement with shoulder 19^b, and as its lower edge clears the shoulder, the 50 spring 19^d through lever 19^c draws the locking device to its normal position and the shoulder 19^b abuts against the lower edge of the locking device. This prevents the 55 key lever from returning to its normal position, preventing the consecutive operation of the same key lever without operating the secondary actuator, and the locking of the key-lever also provides a means for holding 60 a tablet rod in its intermediate or partially elevated position until the secondary actuator engages therewith. When the secondary actuator is operated by opening the till cover, the pin 18^x is moved toward the lever 19^e, and when the till cover is near the 65 end of its opening stroke and the tablet rod has almost reached its full indicating position, pin 18^x strikes lug 19^e, which tilts forward lever 19^e and locking device 19, thus releasing the depressed key lever, the pin 18^x eventually passing over the top of the lug 19^e and free of the same. This action permits spring 18^d to draw arm 18^e forward and tilt the arms 18^a and 18^c, which raises the rod 18^d and the depressed key lever to its normal position, and throws the locking bar 18 against the tablet rods to hold the tablet just actuated in its elevated position. The flexibility of arm 18^c and the free play of the parts permit the pin 18^x to snap back under the lug 19 upon the closing of the till cover.
- 70 It will be observed upon reference particularly to Fig. 1 that the sides of the disks which support the till cover are provided with cams which, when the till cover is entirely open, engage beneath the pins 25^t to lock the bar 18^d positively upward, thereby preventing the depression of the key while the till cover is open.
- 75 Where, in my claims, reference is made to a "cam-ended till cover" I wish it to be understood as including one provided with a cam surface for effecting this function.
- 80 When a tablet rod is elevated, a segment 17 is also moved upward, as before explained, and before that segment can again operate its cooperating primary wheel of the counter, such segment must be returned to its normal position. It will be seen therefore that when a tablet rod descends after the locking bar is disengaged therefrom, the stud 15 moving downward with the tablet rod will permit the segment to drop to its normal position. In order, however, to 85 guard against the sticking of the segment due to friction or any other cause, I provide a device which will positively throw the segment to its normal position. This device consists of two pivoted levers 20, one at each end of the machine, and having a cross-bar 21 which is adapted to engage with the lugs 21^a on the segment shafts 17^x (Fig. 2). The cross-bar 21 is moved forward by the tilting of the levers 20, which tilting action is accomplished by the wiper pawls 22 carried by the arms 12 of the tilting-bar 11, and this tilting action takes place at the beginning of the upward stroke of the secondary actuator; that is to say, referring to Fig. 2, when the lifting-bar 11 is elevated through the opening of the till cover and just before the shoulder 12^b engages with the pin 13, the wiper pawl 22 will strike the cam ends 20^a of the levers 20, tilting the 90
- 95
- 100
- 105
- 110
- 115
- 120
- 125
- 130

same rearward and causing the cross-bar 21 to throw the segments 17 downward by engaging with lugs 21^a; so that before the elevation of a tablet rod begins, all the segments will be in their normal positions.

It will be understood that each of pawls 22 is an ordinary form of wiper pawl pivoted at its center portion and suitably spring-pressed to carry its rearward portion into horizontal position, so that upon the raising of the bar 10 the pawl 22 will strike the inclined surface 20^a and will force the latter rearward since the pawl is now in its blocked position, but as soon as the pawl 15 has been carried up beyond the inclined surface, the lower end of the bar 20 is then free to swing forward as it will when the registering segments are given their full registering movement, and if such lower end of 20 the bar then strikes the pawl 22 it will simply rotate the same about its pivot against its spring tension, and on the downward movement of the bar 10 the pawls 22 will wipe idly by the projections 20^a.

25 In registering any amount, either by a single key or by a number of keys, the depression of the first key will cause the striking of the alarm bell. The alarm bell is indicated at 23 (Fig. 3). The striker 24 is carried by a curved lever 25 which is pivoted at 25^a to the side plate 25^b of the till. The lever 25 has a flange 25^c which is cut away to produce an opening 25^d. The actuating lever 8 is provided with a pin 25^e on 30 the inside, which engages with the flange 25^c, and in the opening movement of the till cover, tilts the lever 25 on its pivot in a direction to move the hammer 24 away from the bell. This movement of the lever 25 causes the pin 25^e on the inner side of the arm 18^e to pass through the opening 25^d, so 35 that when the till cover is closed again, the flanged part 25^b of the lever 25 will rest upon the pin 25^e. The bell hammer is now 40 set to strike the bell, and upon depressing a key lever, which, as before explained, through its engagement with the rod 18^d tilts the arms 18^a and 18^c and carries the arm 18^e backward, so that the pin 25^e will 45 move from under the flange 25^b and in line with the opening 25^d. This releases the lever 25 and permits the spring 25^x (Fig. 3) to operate the bell hammer. The opening movement of the till cover following the depression of a key lever, causes the pin 25^e to pass through the opening 25^d again by reason of the engagement of the pin 25^e with the flange 25^c, and as the pin 18^e strikes the lower end of the arm 18^e to throw the locking bar 18 into engagement with the tablet rods, the pin 25^e is moved under the flange 25^b and the bell hammer is again in position to be tripped by the next key movement.

60 The registering mechanism comprises essentially three normally independent count-

ers or registers for registering units, tens and hundreds. Obviously, additional counters may be employed when the machines are of abnormal capacity. The unit counter is located between the plates P and R. The tens counter is between the plates P' and P and the hundreds counter between the plates R' and P'. These plates P, P', R and R' support and form bearings for all of the transverse shafts of the counting mechanism; the end plates being suitably secured to the main frame of the machine to support said devices.

70 The units and tens counters are similar in all respects and, therefore, a description of the units counter with reference to Figs. 5, 7, 8 and 9 will suffice for both. However, for the hundreds counter I show mechanism of a different type. It may be stated now that this counter also may correspond exactly with the units and tens counters. The segment 17^b, actuated by the unit indicators, meshes with a gear-wheel 30 (Fig. 8), which wheel is rigidly secured to a ratchet-wheel 31. The wheels 30 and 31 are rotated in the direction of the arrow and through the engagement of the pawl 32 with the ratchet-wheel 31 a larger ratchet-wheel 33 is rotated in the same direction. This ratchet-wheel is secured to a gear-wheel 34, shown in dotted lines, which meshes with a large gear-wheel 35 and rotates the same in the direction indicated by the arrow. The gear 35 is carried by a sleeve 35^a loosely mounted on the shaft 35^b and this sleeve carries a register-wheel 36 (see Figs. 5 and 7). The registering-wheel is provided with one or more teeth according to the number of graduations upon the wheel, two teeth 36^a and 36^b being shown in Fig. 7. When the indicating-wheel is provided thereon with the representations of the nine digits and the cipher, it is provided with a single one of these teeth to effect a carrying operation, as will be explained, at each rotation. When it is provided with two sets of figures, it will be provided with two of the carrying teeth as shown. The carrying teeth 36^a, 36^b, engage with and rotate an intermediate carrying wheel or pinion 37, as is common in registering mechanisms. Thus, for every revolution of the registering-wheel, the intermediate carrying-wheel 37 is rotated a distance of one or more spaces according to the number of carrying-teeth on the registering-wheel. The carrying-wheel 37 meshes with a gear-wheel 38 which is rigidly mounted upon the screw 39 so that for every forward movement of the carrying-wheel 37 the screw will be rotated a corresponding distance in the direction of the arrow on the wheel 38.

120 The carrying-wheel 37 is carried by the arm 40 of an L-shaped lever pivoted on the rod 41, and the arm 42 of this lever carries 125

a dog 43 which engages with a ratchet-wheel 44 on the screw 39 when the arm 40 is moved backward to disengage the carrying-wheel 37 from the gear-wheel 38, and permits only a backward movement of the screw, as will be hereinafter described. When the carrying-wheel 37 is in engagement with the gear 38, the pawl 43 will be withdrawn from the ratchet 44 to permit rotation of the screw 39 in its normal direction. On the screw 39 is a traveling nut 45 having an arm 45^a which projects into a slotted bar 46, and, when the screw is rotated, the nut is caused to travel along the same. The screw 39 carries at the left-hand end (see Fig. 5) a wheel 47 which meshes with a gear-wheel 48 loosely mounted on a sleeve 51^a which passes through the plate P. On the left-hand side of the plate the said sleeve carries the gear-wheel 51 and the registering-wheel 52, these two wheels and the sleeve 51^a corresponding to the wheels 35 and 36, and sleeve 35^a of the units register above referred to. To the right of the gear-wheel 48 is rigidly mounted on the sleeve 51^a a ratchet-wheel 50. A pawl 49 carried by the wheel 48 is adapted to engage with the ratchet-wheel 50. In the operation of the units counter, the screw 39 and wheel 47 are rotated in the direction of the arrow on wheel 47 (Fig. 9) and the wheel 48 is rotated about the sleeve 51^a in the opposite direction, the pawl 49 traveling over the ratchet-wheel 50 without affecting it. The limit to the amount that may be stored up on the units counter is determined by the length of the slot in the bar 46, that is to say, when finger 45^a reaches the end of the slot on the left, the units counter cannot be further operated, since the screw, and hence the gearing which drives it, will be locked, and the amount stored up on the units counter must then be transferred to the tens counter. It will be understood that the slotted bar for both the units and tens counter will be provided with a suitable scale with which the arm 45^a on the nuts will cooperate. Since the position of the nuts is dependent upon the extent of movement of the carrying-wheel for the units or tens counter a simple and effective register is secured for effecting registrations on the units or tens counter in excess of the capacity of the registering-wheels 36 or 52.

To transfer the amounts in tens or hundreds thus stored up on the units register to the tens register, the screw 39 is rotated in the opposite direction after first tipping backward the arm 40 of the L-shaped lever 60 so as to disengage the carrying-wheel 37 and to throw the dog 43 into engagement with the ratchet 44 to thus prevent forward movement of the screw 39. Obviously, if the transfer is to be effected, when the finger 45^a is at the left-hand end of its slot, this forward movement of the screw 39 will be prevented, but since the transfer from the units to the tens and from the tens to the hundreds is effected generally when the nuts occupy intermediate positions on their screws, it is necessary to provide independent mechanism like the locking-dogs 43, to overcome the possibility of this movement, which manifestly will result in false registration. By disengaging the carrying-wheel 37 the screw 39 can be readily turned backward without affecting the register-wheel 36 of the units register. The reverse movement of the screw 39 rotates the wheel 47 (Fig. 9) in the direction opposite to the arrow, and that wheel, in turn, rotates the wheel 48 in the opposite direction. This movement causes the pawl 49 to engage the ratchet-wheel 50 which is now rotated in the direction of the arrow on the ratchet-wheel (Fig. 9). This rotation of the ratchet-wheel 50 rotates a wheel 51 and the registering-wheel 52 in the direction of the arrow on the wheel 52 (Fig. 5). Thus, through the backward rotation of the screw 39, the tens counter 52 is moved forward as if its mechanism, corresponding to the parts 30, 31, 33, 34 and 35 of the units counter, were operated by the tens segment 17^a, these parts being caused to rotate in a forward direction. The rotation of the tens counter through the backward rotation of the screw 39 will continue until the nut 45 reaches the limit of its movement to the right. Thus it will be seen that the exact amount represented by the position of the nut will be transferred to the tens counter, but the position of the units wheel representing the units in excess of the tens amount will be unchanged. After the amount stored up in hundreds and tens on the units counter has been thus transferred to the tens counter, the lever 40 is tilted forward again so as to throw the carrying-wheel 37 into mesh with the gear-wheel 38 and disengage the pawl 43 from the ratchet-wheel 44. The units counter will then be in position again to be actuated by its driving segment 17^b. The rotation of the tens counter 52, either through its segment 17^a or through the carrying operation just described, rotates the screw 53 of the tens counter through a set of wheels and ratchets similar to those described in connection with the units counter and for the same purpose and with the same effect, the nut on the screw 53 representing, of course, hundreds and thousands.

To transfer the amounts in hundreds and thousands stored up on the ten counter, lever 54 is tilted backward to disengage the carrying-wheel corresponding to 37 of the units counter and to lock the screw 53 against forward movement as in the units counter. By giving a backward rotation to the screw 53, wheels 55, 56 and 57 are operated in a

manner similar to the operation of wheels 45, 58 and 50 of the units counter, resulting in the forward rotation of the wheel 68 of the hundreds counter which is mounted upon a sleeve similar to the sleeves 35^a and 51^a. The screw 39 extends from the ratchet through the plate R and may be formed on its exposed end with a rectangular section for receiving an ordinary turning-key by which it may be turned backward to carry tens and hundreds from the units to the tens counter. The screw 53 is provided with a reduced extension 53^a extending, as shown, through a plate R' and having a rectangular section at its end receiving a similar key for turning the said screw when a carrying operation is to be effected from the tens to the hundreds counter. The nuts which travel on the screws 39 and 53, when they reach the extreme limit of their slots, lock the units and tens counters against further movement; and, to allow a further registration, the amount stored thereon (in excess of the units on the units counter and of the tens on the tens counter) must be transferred to the hundreds counter by the reverse rotation of the screws 39 and 53. As stated, however, a carrying operation may, and usually does, take place in ordinary operation when the nuts occupy an intermediate position between the extremes of their travel.

It is understood, of course, that the carrying operation is effected whenever the operator sees fit to effect such an operation. The capacity of registration of the traveling nuts in the units and tens counters is limited only by the extent of their movement in the slots and to the pitch of the screws for actuating them. The hundreds counter, as shown in Fig. 5, is of a different character from the units and tens counter simply because it is convenient to make it of a different capacity, and also because of its capability for easy reading. It will be understood, however, that a counter may be used for registering hundreds similar in all respects to the units and tens counter above described. The counter shown is provided with four registering-wheels 69, 70, 71 and 72, the first of which is on the sleeve carrying the gear-wheel 68 like the counter 52 and gear-wheel 51 of the tens counter, or the counter 36 and gear-wheel 35 of the units counter. The other three registering-wheels of the hundreds counter are loosely mounted on a shaft 35^b, and each of these register-wheels has formed integrally therewith or rigidly attached thereto, a gear-wheel which is in mesh with the carrying-wheels 69^b, 70^b and 71^b respectively. These carrying-wheels are loosely mounted on a rod 74^a, carried between two arms 74, which arms are rigidly mounted upon a rod 74^b. The lever 73 is rigidly attached to the rod 74^b to tilt the arms 74 and disengage the carrying-wheels from the register-wheels when it is desired to turn the latter to zero. The register-wheels 69, 70 and 71 are provided, respectively, with one or more teeth 69^b, 70^b and 71^b which are adapted to engage with and actuate the carrying-wheels referred to. If the register-wheels are provided with two of such teeth, the carrying-wheels will be actuated a distance of one space for each half-revolution of the corresponding register-wheel which will cause rotation of the next higher register-wheel a distance of one space for every half-revolution of the former. The gear-wheel 68 of the hundreds counter is driven by a series of gear-wheels and register-wheels similar in all respects to those described in connection with the units and tens counters. These parts are shown at 63, 64, 65, 66 and 67, which correspond respectively with the parts 30, 31, 32, 33 and 34 of the units counter shown in Figs. 7 and 8. The segment 17, which actuates the hundreds counter, engages with the gear-wheel 63. To return the hundreds counter to zero, the lever 73 is tilted forward, which movement tilts the arms 74 downward and disengages the carrying-wheels and the register-wheels, whereupon the register-wheels may be turned by hand to zero. The levers 40, 54 and 73 are provided with pins which engage with holes in the plates 75, 76 and 77, to lock the levers in the proper position. In Fig. 7, the two holes are shown at 75^a, 75^b, and the pin on the lever 40 at 40^a, the pin being in engagement with the hole 75^a which is the position of the lever when the carrying-wheel 37 is in position to drive the gear-wheel 38. The pin on the lever 73 is shown at 73^a and one of the holes in plate 77 is shown in dotted lines at 77^b, the pin 73^a being in the other hole. The counters are driven by the segments 17, 17^a and 17^b to operate them directly, to register hundreds, tens and units sales respectively. The gear-wheels 48 and 56 are not rotated upon the operation of the segments since they are loose on the sleeves 35^a and 68^a respectively, and hence the operation of the hundreds and tens counters by the segments 17 and 17^a cannot affect the screws 53 and 39 respectively; and, as before stated, during the forward movement of the screws 39 and 53, when the units and tens counters, respectively, are driven by their segments 17^b and 17^a, the gear-wheels 48 and 56 are rotated without affecting the tens and hundreds counters 52 and 68, since the wheels 48 and 56 are rotated in the direction of the arrow (Fig. 9) and the pawls, which engage with the ratchet-wheels 50 and 37, respectively, travel over those wheels without affecting them. It is only upon the reverse or backward rotation of the screws 39 and 53 that

the tens and hundreds counters are affected through the engagement of the gear-wheels 47 and 48 of the units counter and 55 and 56 of the tens counter.

- 5 The operation of the improved registering mechanism, in connection with the operation of the parts of the improved cash register, have been indicated in the foregoing description and need not be described in detail here.
- 10 It will be understood that in the registration of unit sales, the operation of the cash register will effect a direct registration on the units counter. The same is true of the tens and hundreds counters for the direct registration of the tens and hundreds sales. At the end of its operation the units counter will indicate in units, tens or higher denominations, the total of the unit sales for the day or any other period as may be desired.
- 15 The tens counter will indicate, not only in tens but in higher denominations, the total of the tens sales during that period. The hundreds counter will indicate the total of the hundreds sales during this period. In order that the operator may have a total of all the sales for his convenience, or in order that the device may have the capacity for continuing its operation, if the nuts of either the units or tens counters have reached the limit of their travel, the carrying operation is effected by reversing the rotation of the screws 39 and 53. By reversing the rotation of the screw 39, the total represented by the units counter in excess of a unit amount 20 on the register disk 36 will be transferred to the tens counter, the nut 45 being returned to its zero position. By reversing the rotation of the screw 53, the nut of the tens counter will be returned to the zero position and 25 the amount indicated by the tens counter in excess of the tens amount on the register disk 52 will be transferred to the hundreds counter. The hundreds counter, therefore, indicates in total net only the amount in 30 hundreds directly registered thereon by the operation of the machine, but also the amount in hundreds transferred thereto from the tens counter. The register disks 52 and 36 of the tens and units counters will, 35 therefore, represent in tens and units the amount in excess of that transferred to the hundreds counter. The operator thus has a total on the three counters of the sales consummated during any desired period. The 40 value of this improvement will be apparent. The operator is, in the first instance, informed of the totals of the individual counters while, at the same time, he is allowed, by the operation of means independent of 45 the operation of the cash register, to effect a totalization of the amounts, as I have explained.

I wish it understood that I do not consider my invention as limited to machines 50 in which the cash receptacle is exposed by

the movement of a movable lid. It is well within the scope of this invention to operate the several devices by a movable cash drawer or another movable part of a cash safe whose movement exposes the cash.

What I claim is:

1. In a cash register, the combination with indicators normally inexposed, of a primary actuator for moving an indicator to an intermediate or partly exposed position, a device 70 for locking said primary actuator against movement after actuating an indicator, whereby the indicator is held in the intermediate position, a secondary actuator for completing the movement of the indicator to the exposed position, and means for releasing the primary actuator, substantially as set forth.
2. In a cash register, the combination with indicators normally inexposed, of key 75 levers for moving said indicators to an intermediate or partly exposed position by a complete operative stroke of the key, a device for locking the key levers when depressed to hold the indicators in the intermediate 80 position, and means for completing the movement of the indicators to the exposed position, substantially as set forth.
3. In a cash register, the combination with indicators normally inexposed, of key levers 85 for moving said indicators to an intermediate or partly exposed position by a complete operative stroke of the key, a device for locking the key levers when depressed to hold the indicators in the intermediate 90 position, means for completing the movement of the indicators to the exposed position, and means for releasing the locked key lever when the indicator reaches the end of its second movement, substantially as set 95 forth.
4. In a cash register, the combination with indicators normally inexposed, of key levers for moving said indicators to an intermediate or partly exposed position, a device 100 for locking the key levers when depressed to hold the indicators in the intermediate position, a till, and means operated through the opening of the till for completing the movement of the indicators to the exposed 105 position, substantially as set forth.
5. In a cash register, the combination with indicators normally inexposed, of key levers for moving said indicators to an intermediate or partly exposed position, a device 110 for locking the key levers when depressed to hold the indicators in the intermediate position, a till, means operated through the opening of the till for completing the movement of the indicators to the exposed 115 position, and a device actuated by the opening of the till to release the locked key lever, substantially as set forth.
6. In a cash register, the combination with a tablet rod whose tablet is normally inex- 120

- posed, of a pivoted key lever adapted to engage said rod to elevate the tablet to an intermediate position, a device for locking the key lever when depressed to hold the tablet in the intermediate position, a till a lifting-bar actuated by the opening of the till to move the tablet to its exposed position, and means for releasing the locked key lever, substantially as set forth.
- 5 7. In a cash register, the combination with indicators normally inexposed, of key levers for moving said indicators to an intermediate or partly exposed position by a complete operative stroke of the key, a device for locking the key levers when depressed to hold the indicators in the intermediate position, means for completing the movement of the indicators to the exposed position, a locking bar for holding the indicator in its exposed position, and means for releasing an exposed indicator to permit its return to the normal position, substantially as set forth.
- 10 8. In a cash register, the combination with indicators normally inexposed, of key levers for moving said indicators to an intermediate or partly exposed position by a complete operative stroke of the key, a device for locking the key levers when depressed to hold the indicators in the intermediate position, means for completing the movement of the indicators to the exposed position, a locking bar for holding the indicator in its exposed position, and means 15 operated by the key levers for releasing an exposed indicator to permit its return to the normal position, substantially as set forth.
- 15 9. In a cash register, the combination with the tablet rods whose tablets are normally inexposed, of pivoted key levers adapted to engage the tablet rods to elevate the same to an intermediate position, a locking device for locking the key levers against movement when depressed and to hold the tablet rods in the intermediate position, a lifting-bar for completing the movement of the tablet to the exposed position, and a pivoted locking-bar for holding the tablets in the exposed position, and which bar is 20 tripped through the depression of a key lever to release an exposed tablet and permit its return to normal position, substantially as set forth.
- 25 10. In a cash register, the combination with the tablet rods whose tablets are normally inexposed, of pivoted key levers adapted to engage the tablet rods to elevate the same to an intermediate position, a locking device for locking the key levers against movement when depressed and to hold the tablet rods in the intermediate position, a lifting-bar for completing the movement of the tablet to the exposed position, a device 25 for releasing a locked lever when its tablet reaches the end of its second movement, and a pivoted locking-bar for holding the tablets in the exposed position, and which bar is tripped through the depression of a key lever to release an exposed tablet and permit its return to normal position, substantially as set forth.
- 30 11. In a cash register, the combination with a money receptacle, of the tablet rods provided with indicating tablets normally inexposed, a primary actuator for moving the tablet rods out of normal position in a direction only substantially parallel with the plane of final movement, and into position, to be engaged by a secondary actuator, comprising a swinging bar adapted to be moved into engagement with a shifted tablet rod, and means controlled by the exposure of the money receptacle for actuating said bar to move the shifted tablet to exposed position, substantially as set forth.
- 35 12. In a cash register, the combination with a money receptacle, of the tablet rods provided with indicating tablets normally inexposed, a primary actuator for moving the tablet rods out of normal position in a direction only substantially parallel with the plane of final movement and into position to be engaged by a secondary actuator, means whereby the tablet rods are held in the position to which they are shifted by the primary actuator, and a secondary actuator comprising a swinging bar adapted to be moved into engagement with a shifted tablet rod, and means controlled by the exposure of the money receptacle for actuating said bar to move the shifted tablet to exposed position, substantially as set forth.
- 40 13. In a cash register, the combination with a till having a rotary cover, tablet rods provided with indicating tablets normally inexposed, keys for moving the tablet rods out of normal position in a direction only substantially parallel with the plane of final movement, a swinging lifting bar adapted to be moved into engagement with a shifted tablet rod, and means operated by the till cover for actuating said lifting bar and moving the tablet rods to exposed position, substantially as set forth.
- 45 14. In a cash register, the combination with a till having a rotary cover, tablet rods provided with indicating tablets normally inexposed, keys for moving the tablet rods out of normal position in a direction only substantially parallel with the plane of final movement, means for holding the tablet rods in the position to which they are moved by the keys, a swinging lifting bar adapted to be moved into engagement with a shifted tablet rod, and means operated by the till cover for actuating said lifting bar and moving the tablet rods to exposed position, substantially as set forth.
- 50 15. In a cash register, the combination with the till, tablet rods provided with in-

- dicating tablets normally in-exposed, and keys for controlling the setting of said tablets to exposed position, of a bar for supporting the tablets in the exposed position, means whereby said bar is moved into supporting position upon the opening of the till, and means for moving such bar out of supporting position, substantially as set forth. 5
16. In a cash register, the combination with the till, tablet rods provided with indicating tablets normally in-exposed, and keys for controlling the movement of said tablets to exposed position, of a bar for supporting the tablets in the exposed position, means whereby said bar is moved into supporting position by the opening of the till, and means activated by the keys for moving said bar out of supporting position, substantially as set forth. 10
17. In a cash register, the combination with the till, tablet rods provided with indicating tablets normally in-exposed, and keys for controlling the movement of said tablets to exposed position, of means for moving the tablets to exposed position independently of the keys, a bar for supporting the tablets in the exposed position, means whereby said bar is moved into supporting position upon the opening of the till, and means activated by the keys for moving said bar out of supporting position, substantially as set forth. 15
18. In a cash register, the combination with a till having a movable cover, tablet rods provided with indicating tablets normally in-exposed, and keys for controlling the movement of said tablets to exposed position, of means activated by the movable till cover for moving the tablets to exposed position, whereby said bar is moved into supporting position upon the opening of said cover, and means activated by the keys for moving said bar out of supporting position, substantially as set forth. 20
19. In a cash register, the combination with a till having a rotary cover, tablet rods provided with indicating tablets normally in-exposed, and keys for controlling the movement of said tablets to exposed position, of means activated by the rotary till cover for moving the tablets to exposed position, a bar for supporting the tablets in the exposed position, means whereby said bar is moved into supporting position upon the opening of said cover, and means activated by the keys for moving said bar out of supporting position, substantially as set forth. 25
20. In a cash register, the combination with a till, tablet rods provided with indicating tablets normally in-exposed, and keys for controlling the movement of said tablets to exposed position, of a locking-bar carried by pivoted levers for locking the tablets in the exposed position, and a second bar carried by said levers and located so as to be activated by the keys to move the first named bar out of locking position and permit an exposed tablet to return to its normal or in-exposed position, substantially as set forth. 30
21. In a cash register, the combination with a till having a rotary cover, tablet rods provided with indicating tablets normally in-exposed, and keys for controlling the movement of said tablets to exposed position, of a locking-bar carried by pivoted levers for locking the tablets in the exposed position, means moved by the cover for moving said locking-bar into locking position, and a second bar carried by said levers located so as to be activated by the keys to move the first named bar out of locking position and permit an exposed tablet to return to its normal or in-exposed position, substantially as set forth. 35
22. In a cash register, the combination with a series of keys, of indicating tablets, a rotary cover under the till cover, a lever provided at one part with a first bar for engaging with and supporting tablet rods at another part with a cross-bar to engage with the key levers, and at another part with means for engaging the rear end of the till cover, whereby under the action of the till cover, part of said bars readjusts the key and till cover so located while the till is open, and under the action of the keys while the till is closed, the tablets are dropped, substantially as described. 40
23. In a cash register, the combination with a till, the keys and a bell, of means actuated by the till for setting the bell bumer, and means activated by the keys for tripping the bell bumer, substantially as set forth. 45
24. In a cash register, the combination with the till, a cover therefor, the keys and a bell, of a pivoted spring-retained lever carrying the hammer for striking the bell, means carried by the till cover for engaging said lever to of the bell bumer, and a device activated by the key levers for tripping said lever, substantially as set forth. 50
25. In a machine of the class described, the combination with a totalizer comprising a plurality of denominational elements, of means for directly actuating said elements, an accumulating device for each of said elements, and means for transferring amounts from one accumulating device to another. 55
26. In a machine of the class described, the combination with a totalizer comprising a plurality of denominational elements representing units, tens and hundreds, of means for entering thereto amounts corresponding to such denominations, an accumulating device for each of said denominational elements, and means for transferring the amount stored upon the accumulating device of the units element to the tens element. 60

accumulating device and from the latter device to the accumulating device of the hundreds element.

27. In a machine of the class described, the combination with a totalizer comprising a plurality of denominational elements representing units, tens and hundreds, of means for entering thereon amounts corresponding to such denominations, an accumulating device for each of said denominational elements, and means for transferring through the tens element to its accumulating device the amount stored upon the units accumulating device and thence from the tens accumulating device through the hundreds element to the accumulating device of the latter element.

28. In a machine of the class described, the combination with a totalizer comprising a plurality of elements of progressively higher denominations, of means for actuating said elements, an accumulating device for each element, and means for transferring an amount stored upon an accumulating device of a lower denomination to an accumulating device of a higher denomination through the companion element of the latter device.

29. In a counter or registering mechanism, the combination with two register wheels representing different denominations, of means for directly registering thereon amounts corresponding to such denominations, mechanism cooperating with the register wheel of each denomination for accumulating amounts in excess of the capacity of said register wheels, and means for reversing the movement of the accumulating mechanism of lower denomination for transferring the excess amount thereon to the accumulating device of the higher register wheel.

30. In a counter or registering mechanism, the combination with three register wheels representing units, tens and hundreds, of means for registering thereon amounts corresponding to such denominations, mechanism cooperating with each wheel for accumulating amounts in excess of the capacity of said wheels, and means for reversing the movement of the accumulating mechanisms of the units and tens register wheels for transferring to the hundreds accumulating mechanism the excess amounts stored upon the units and tens accumulating mechanisms.

31. In a counter or registering mechanism, the combination with two register wheels representing different denominations, of means for registering thereon amounts corresponding to such denominations, means comprising a screw and a nut controlled by the register wheel of lower denomination for accumulating amounts in excess of the capacity of said register wheel, a similar means for accumulating counts in excess

of the capacity of the register wheel of higher denomination, and means for reversing the registering movement of the accumulating means controlled by the wheel of the lower denomination for transferring the excess amount stored thereon to the accumulating means of the higher denomination.

32. In a counter or registering mechanism, the combination with three wheels representing units, tens and hundreds, of means for directly registering thereon amounts corresponding to such denominations, mechanism comprising a screw and nut controlled by the units wheel for accumulating amounts in excess of the capacity of said wheel, similar accumulating mechanisms cooperating with the tens and hundreds wheels, and means operable at will for transferring the amount stored on the accumulating mechanism of the units wheel to the tens wheel accumulating mechanism and from the latter mechanism to the accumulating mechanism of the hundreds wheel.

33. In a counter or registering mechanism, the combination with two register wheels representing different denominations, of means for registering thereon amounts corresponding to such denominations, mechanism comprising a screw and nut normally connected to the register wheel of lower denomination for accumulating amounts in excess of the capacity of said register wheel, a similar accumulating mechanism for the wheel of higher denomination, means for disconnecting the wheel of lower denomination from its companion accumulating mechanism, and means for transferring the excess amount on the accumulating mechanism of lower denomination to the accumulating mechanism of higher denomination while the first mentioned accumulating mechanism is disconnected from its register wheel.

34. In a counter or registering mechanism, the combination with a register-wheel, of an operating device for giving said register wheel a differential movement, a carrying pinion operated intermittently by said wheel as it completes certain portions of its revolution, a screw operated by said carrying pinion and a nut on said screw representing amounts in excess of the capacity of said wheel.

35. In a counter or registering mechanism the combination with a register-wheel, of an operating device for giving said register wheel a differential movement, a carrying pinion operated intermittently by said wheel, a screw operated by said carrying pinion, a nut on said screw representing amounts in excess of the capacity of said wheel, and means for disconnecting the carrying pinion from said register-wheel, whereby return movement of said screw will be permitted.

36. In a cash register, the combination with a counter of a series of tablet-rods and

mechanism for lifting them to indicating position, of a rack adapted to be actuated by said tablet rods to operate the counter, and means actuated by the lifting mechanism of the tablet rods for moving said rack toward its normal position after operating the counter, substantially as set forth.

35. In a cash register, the combination with a series of tablet rods, of means carried by said rods for actuating a rack to operate a counter, a locking device for holding the tablet rods in their elevated position, a lifting bar for elevating said tablet rods and a device actuated by said lifting bar to insure the return of said rack toward its normal position upon the release of a tablet rod from its elevated position, substantially as set forth.

36. In a registering mechanism, the combination with a plurality of independent counters, of means for registering amounts thereon, and means operated at will for transferring amounts from a number of the counters to a single one of the same.

37. In a cash register, the combination with a series of independent counters representing different denominations, means for registering amounts on the different counters and means operated at will for transferring like denominational amounts from counters of certain denominations to the counters of the next higher denominations.

38. In a cash register, the combination with a series of independent denominational counters, each comprising a register wheel and an accumulating device, of means for registering amounts on said counters, and means operated at will for transferring the amount on each accumulating device to the register wheel of the next higher denomination.

39. In a cash register, the combination with a series of indicators, of a primary actuator for moving an indicator to an intermediate or partly exposed position, a secondary actuator for completing the movement of the indicator to the exposed position, graduated projections on said indicators, a frame carrying a gear segment and adapted to be actuated by said projections and counter-constructed to the segment.

40. In a cash register, the combination with a series of indicators provided with graduated lifting projections, of a primary actuator for moving an indicator to an intermediate or partly exposed position, a device for locking said primary actuator against movement after it has partly actuated an indicator whereby the indicator is held in the intermediate position, a secondary actuator for completing the movement of the indicator to the exposed position, a frame extending across said indicators and adapted to be actuated by the lifting pro-

jections thereof, a gear segment carried by said frame, and a counter-constructed to be operated by said gear.

41. In a cash register, the combination with a series of indicators, of keys for moving said indicators to an intermediate setting position, a device for holding the keys when depressed to hold the indicators in the intermediate position and a till having a movable part for continuing the movement of the indicator and for operating the key locking device.

42. In a cash register, the combination with indicators normally exposed, of a primary actuator for moving an indicator upward toward its exposed position, and a second independent actuator constructed to kick in such indicators as have been moved upward toward exposed position, and complete their movements to fully expose them.

43. In a cash register, the combination with a series of indicators vertically movable to exposed positions, of means for directly engaging and lifting said indicators a slight vertical movement, and a second so independent actuator constructed to directly engage and elevate such indicators as have already been partly elevated.

44. In a cash register, the combination with a series of indicators arranged to be moved vertically to exposed positions, of means for moving said indicators a partial vertical movement, and a second independent actuator arranged to move them vertically, and laterally to engage and elevate such indicators as have already been partially elevated.

45. In a cash register, the combination with a safe having a movable part of indicators which are normally exposed, keys for controlling the setting of the indicators to exposed positions, detents for holding the indicators in their exposed positions, means whereby said detents are moved into holding positions by the action of the movable part of the cash safe, and devices for moving said detents out of their holding positions.

46. In a cash register, the combination with a cash safe having a movable part, of a series of indicators which are normally exposed, controlling keys, detents for holding the indicators in their exposed positions, means whereby said detents are moved into holding positions by the action of the movable part of the cash safe, and means for moving the detents to disengage them from the indicators by the operation of a key.

47. In a cash register, the combination with a cash safe having a movable part, of a series of indicators which are normally exposed, controlling keys for the indicators, detents for holding the indicators in their exposed positions, means operated by

- the movable part of the cash till for positively forcing the detents into engagement with the indicators, and means operated by the keys for disengaging the detents from 5 the indicators.
50. In a cash register, the combination with a plurality of denominational registering wheels, of actuators therefor, a device for each wheel for accumulating 10 amounts in excess of the capacity of said wheel, connections between each registering wheel and its accumulating device, means for resetting each accumulating device and thereby transferring the amount thereon to 15 the registering wheel of next higher denomination, and means for disabling the connections between any one of the wheels and its accumulating device when it is desired to transfer the amount on the latter device to 20 the registering wheel of the next higher denomination.
51. In a cash register, the combination with a registering device, comprising a series of registering elements, with means for 25 actuating said elements, of transfer storing mechanism operated by said elements, and moved thereby from its normal position during its storing movement, means for returning said storing mechanism to its normal 30 position, with devices whereby the returning of said storing mechanism actuates a registering element of higher denomination than that which operated the storing mechanism from its normal position.
52. In a cash register, the combination with a plurality of denominational registering wheels, of actuators therefor, a device for each wheel for accumulating amounts in excess of the capacity of said wheel, 35 means for resetting the accumulating devices to zero, connections between each accumulating device and the registering wheel of next higher denomination whereby the amount accumulated on said device will be transferred to said wheel when the accumulating device is reset, and means preventing movement of the accumulating device in any other but a resetting direction when an amount is to be transferred therefrom.
53. In a cash register, the combination with a counter comprising a plurality of registering elements, with means for registering amounts on each of said elements, of a transfer registering device actuated by one 40 of said elements, means for restoring said transfer device to its original position after actuation thereof, and means operated by the restoration of said transfer device for actuating an additional one of said registering elements to differential extents.
54. In a cash register, the combination with a counter comprising a plurality of denominational registering elements, of means for registering amounts thereon, an 45 accumulating device for each of said ele-
- ments, connections whereby said elements drive said accumulating devices, means for restoring said accumulating devices to normal position after actuation thereof, and connections whereby said restoring movement transfers the amounts on said accumulating devices to the registering elements of next higher denominational orders. 50
55. In a machine of the class described, the combination with a plurality of accumulating devices, of actuating mechanism therefor, and means operable at will for transferring to a single one of said devices the accumulations of the remaining devices whereby a grand total is obtained. 55
56. In a machine of the class described, the combination with an operating mechanism, of an accumulating device, a bank of keys, connections driven by said operating mechanism under the control of the keys for 60 actuating said accumulating device, a second accumulating device, means for giving a resetting movement to said first accumulating device and thereby transfer the amount thereon to the second accumulating device, and a manipulative device for disabling the above mentioned connections previous to the resetting movement of the first accumulating device. 65
57. In a machine of the class described, the combination with an operating mechanism, of an accumulating device, a bank of keys, connections driven by said operating mechanism under the control of the keys for 70 actuating said accumulating device, a second accumulating device, means for giving a resetting movement to said first accumulating device and thereby transferring the amount thereon to the second accumulating device, a manipulative device for disabling the above mentioned connections driven by the operating mechanism previous to the resetting movement of the first accumulating device, resetting mechanism for the second accumulating device, and means controlled by 75 the resetting the latter device for retaining in the machine the accumulations on said device. 80
58. In a machine of the class described, the combination with a first and a second accumulating device, of means for directly actuating the first accumulating device, means for causing reverse movements of the first accumulating device, connections for causing the extent of reverse movements of said 85 device to be measured by the second accumulating device, means for causing reverse movements of the latter device, and mechanism controlled by the reverse movements of the second device for retaining in the machine an entry of the accumulations on 90 said second accumulating device. 95
59. In a machine of the class described, the combination with a plurality of accumulating devices, of operating mechanism 100

therefor, and means, including an element of the aforesaid mechanism, operated at will for transferring to a single one of said devices the accumulations of the remaining devices.

60. In a machine of the class described, the combination with a plurality of accumulating devices, of operating mechanism therefor, and means, including an element of the aforesaid mechanism, operated at will for transferring the accumulation of one device to another one of said devices.

61. In a registering mechanism, the combination with two independent counters, of means for registering amounts thereon, and

means operated at will for transferring amounts from one of said counters to the other.

62. In a registering mechanism, the combination with two independent counters, of means for differentially operating the same, and means operated at will for transferring amounts from one of said counters to the other.

In testimony whereof, I sign this specification in the presence of my witnesses.

FRANCIS G. OSBORN.
